UNITED STATES PATENT OFFICE.

WILHELM GAUS, OF LUDWIGSHAFEN-ON-THE-RHINE, GERMANY, ASSIGNOR TO BADI-
SCHE ANILIN & SODA FABRIK, OF LUDWIGSHAFEN-ON-THE-RHINE, GERMANY, A
CORPORATION.

REDUCING INDIGO COLORING-MATTERS.

1,027,836.

Specification of Letters Patent. Patented May 23, 1912.

No Drawing.

Application filed June 9, 1910. Serial No. 565,987.

To all whom it may concern:

Be it known that I, WILHELM GAUS, a subject of the King of Prussia, residing at Ludwigshafen - on - the - Rhine, Germany, have invented new and useful Improvements in Reducing Indigo Coloring-Matters, of which the following is a specification.

The specification of Letters Patent No. 820,900 describes the reduction of indigo and similar coloring matter by treating it with iron powder in a caustic alkali solution which contains at least 6.5 per cent. of solid caustic alkali, and the specification of Letters Patent No. 843,566 describes a modification of the aforesaid process in which, a part, or the whole, of the alkali is replaced by an alkali salt of indigo white, or by an alkali carbonate, or alkali phosphate, or alkali sulfid. When either of the aforesaid processes is being carried out, it has been found in some cases that the action of the iron powder is in so far unreliable that it will sometimes happen that the iron powder (say, powdered cast iron turnings), even after having been freed from oily impurities, does not always produce the best results, although the iron powder behaves normally if the reduction be carried out in the presence of acid. I have found that the said unreliability can be remedied and good results be always obtained when reducing indigo, or similar coloring matter, with iron powder in the presence of alkali, or an alkaline salt, as aforesaid if the iron powder, before being used for the reduction, be treated with an acid.

This invention can be applied to iron powder generally and to iron residues, such as are obtained in chemical processes and under other conditions.

It is possible that the inability of the iron satisfactorily to reduce the indigo or similar coloring matter may be due to a thin layer of ferric oxid covering the iron, and that the acid dissolves away this layer of ferric oxid, so that the metallic iron can then exert its reducing effect upon the indigo, or similar coloring matter.

The following example will serve to illus-

trate further the nature of my invention and how it can be carried into practical effect, but the invention is not confined to this example. The parts are by weight. Stir three hundred parts of very finely ground cast-iron turnings (after having freed them, if necessary, from oil by treating them with carbon tetrachlorid) with one thousand parts of water, and then, while well agitating the mixture, add eighteen per cent. sulfuric acid, until a considerable evolution of hydrogen commences. Then allow the iron powder to settle, remove the acid liquor and wash the iron several times with water. The iron paste so obtained can be employed in the reduction of indigo, or similar coloring matter, in the manner described in the aforesaid specifications.

Now what I claim is:—

1. The process of reducing indigo coloring matters by means of iron which consists in first pickling the iron with an acid and then heating the indigo coloring matter in the presence of alkali with the iron which has been thus treated, substantially as hereinbefore described.

2. The process of reducing indigo coloring matters by means of iron which consists in first pickling the iron with an acid and then heating the indigo coloring matter in the presence of caustic alkali with the iron which has been thus treated, substantially as hereinbefore described.

3. The process of reducing indigo coloring matters by means of iron which consists in first pickling the iron with an acid and then heating the indigo coloring matter in the presence of caustic alkali solution (which contains at least 6.5 per cent. of solid caustic alkali) with the iron which has been thus treated, substantially as hereinbefore described.

In testimony whereof I have hereunto set my hand in the presence of two subscribing witnesses.

WILHELM GAUS.
